UNITED STATES PATENT OFFICE

FRANK P. BERGER, OF CHICAGO, ILLINOIS, ASSIGNOR TO BERGER DEVICE MFG. CO. INC., OF CHICAGO, ILLINOIS, A CORPORATION OF ILLINOIS

GAS OR THE LIKE VENTING DEVICE

Application filed April 11, 1927. Serial No. 182,704.

My invention relates in general to gas or the like venting devices and has particular reference to a gas venting unit for use in combination with kegs or like containers used 5 for the fermentation of certain liquids. As heretofore practiced, venting devices of this character usually rely on the so-called water-seal for air trapping purposes for permitting escape of gas from the keg or container in 10 which the fermenting liquid is contained with the seal excluding air from the container. This principle is practical under ordinary conditions, but I have found that unless the venting device is equipped with means, such 15 as a pressure responsive control, it sometimes happens that due to change of temperatures there is a tendency for the atmospheric pressure to force the water in the venting unit into the keg or container, thus spoiling the 20 liquid, as well as destroying the function of the venting device.

The primary object of this invention is to provide a venting device with means to fore-stall any possibility of the atmospheric pressure 25 sure on the outside of the keg forcing the water in the venting unit into the keg and the preferred construction for accomplishing this feature is illustrated in the accompanying drawing, in which

30 Fig. 1 is a view in side elevation of the venting unit;

Fig. 2 is a similar view, with parts in section;

Fig. 3 is a detail perspective view of the 35 valve cap; and

Fig. 4 is a detail perspective view of the disc valve.

Referring now to the drawing in detail, 5 represents a bung plug which is of more or less conventional construction, the same being made of wood and being adapted to be driven into the bung hole of a keg. These plugs may be made in various sizes so as to be accommodated in different sized bung 10 holes. For the purpose of the present invention the bung 5 is made with a central opening 6 extending from end to end of the plug and made to receive a tube 7 which is bent upon itself as at 8 to provide a depending 15 end 9. The end 9 is intended to pass through

an opening 10 in a rubber stopper 11, as an example, in a glass water bottle 12. The stopper 11 is made with a normally open air escape 13.

Carried on the depending end 9 of the 55 tube 7 is a venting head 14, the same being adapted to be submerged in the water contained in the bottle 12 and having a central bore 15 for the reception of the end of the tube so that the head is thus suspended from 60 the tube end, preferably above the bottom of the water bottle 12. The venting head 14 may be constructed in various ways and in most cases I would prefer to produce the same from a frustum-shaped piece of metal 65 with the bore 15 drilled in the center of the piece. The flat top of the head 14 is made to provide a seat for a disc valve 16, the valve being produced preferably from flexible material, rubber, as an example, and 70 having an opening 17 through which the tube 9 extends into the bore 15. The fit between the tube and the opening 17 in the valve should be free enough to permit the valve to slide on the tube, unless the valve is so flexible as to readily respond to pressure of the 75 gas discharged into the venting head 14 and from which it escapes through the gas vent 18. The gas vent 18 is disposed in the head at one side of the bore 15 and communicates 80 with the bore internally of the head, as at 19.

Overlying the disc valve 16 is a cap 20 having a short upstanding boss 21 around the opening 22 through which the tube extends. With this construction the cap is also slidably 85 mounted on the tube, so to speak, and resting upon the valve 16 which, of course, overlies the gas vent 18 and closes the same. The valve 16 is adapted to uncover the gas vent 18 in response to gas pressure generated in 90 the keg or container so that the gas escapes through the water-seal and out through the opening 13 in the stopper 11.

If there should happen to be a drop in 95 temperature in the contents of the liquid in the keg, the tendency would be for the gases in the keg to contract, causing atmospheric pressure to force the water in the bottle through the venting head into the tube and thus into the keg, where it would more than 100

likely spoil the liquid and also leave the air trap open to such an extent that air would readily enter the keg through the venting unit after the water in the bottle has been forced out. This latter possibility would not be apt to cause a great deal of damage unless the device was left unattended for some time, but since this frequently happens it is a possibility that must be taken into account.

10 With my pressure responsive control the possibility of water being forced into the keg need not be considered, since the valve 16 in overlying the gas vent 18 in the venting head will operate to normally seal the gas vent 18 until the pressure of the escaping gas from the keg is sufficient to raise the same from its seat and expose the gas vent a sufficient amount to permit the escape of the generating gas. When the gas pressure in 15 the keg drops, the valve closes the gas vent and prevents any water from passing into the venting head and tube.

The cap 20 should be used in combination with the valve 16 when the latter is constructed of flexible material, such as rubber. However, the cap may be dispensed with if the valve is stiff enough and heavy enough to maintain its seat without wrinkling. The valve 16, as well as the cap 20, should not 20 be too heavy, otherwise it would not open the gas vent in response to the slight pressure of a small amount of escaping gas. In other words, the valve will act automatically to close the gas vent 18 as soon as there is any 25 back pressure to be accounted for and it does not depend on any float or buoyancy of the material. It is always closed, except when sufficient pressure is exerted outwardly from the keg through the tube to lift the cap to 30 allow the gas caused by fermentation of the liquid to escape through the water-seal in the bottle 12.

I claim:

1. In a gas or the like venting device, a 45 vent head adapted to be submerged in a liquid seal and having an opening for the reception of a gas pipe and making a liquid tight seal therewith, a gas vent passing through said head communicating with the opening for 50 the gas pipe, and a pressure responsive control for said vent, comprising a cover-piece overlying the vent and a cap overlying the cover-piece.

2. In a gas or the like venting device, a 55 one piece vent head adapted to be immersed in a liquid and having a bore for the reception of a gas pipe and making a liquid tight seal therewith, a gas vent passing through said head to one side of said bore communicating with the bore interiorly of the vent head, and a pressure responsive control for 60 said vent, comprising a cover-piece movably mounted with respect to the vent head and adapted to overlie the gas vent and to be held 65 in that position by the pressure of said liquid.

3. In a gas or the like venting device, a one piece vent head adapted to be submerged in a liquid seal and having a bore for the reception of a gas pipe and making a liquid tight seal therewith, a gas vent passing 70 through said head to one side of said bore communicating with the bore interiorly of the vent head, a pressure responsive control for said vent, comprising a cover-piece movably mounted with respect to the vent head 75 and adapted to overlie the gas vent, and a cap also movably mounted with respect to the vent head adapted to overlie the cover-piece.

4. In a gas or the like venting device, a 80 one-piece vent head adapted to be submerged in a liquid seal and having a bore for the reception of a gas pipe and making a liquid tight seal therewith, a gas vent passing through said head communicating with said 85 bore, and a pressure responsive control for said vent, comprising means on the outside of the head covering the gas vent, said means being liftable with respect to the vent in response to gas pressure discharging from 90 the vent but adapted to close the vent in response to pressure from the outside of the vent.

5. In a gas or the like venting device, a 95 vent head having a bore, a gas pipe communicating therewith, a gas vent in said head to one side of the gas pipe and communicating therewith internally of the vent head, and a pressure responsive control for said 100 gas vent, comprising a cover therefor mounted on the vent head through the medium of an opening therein through which the gas pipe extends.

6. In a gas or the like venting device, a 105 vent head having a bore, a gas pipe communicating therewith, a gas vent in said head to one side of the gas pipe and communicating therewith internally of the vent head, and a pressure responsive control for said 110 gas vent, comprising a cover therefor mounted on the vent head through the medium of an opening therein through which the gas pipe extends and relatively light weight overlying said cover.

7. In a gas or the like venting device, a 115 vent head having a bore, a gas pipe communicating therewith, a gas vent in said head to one side of the gas pipe and communicating therewith internally of the vent head, a pressure responsive control for said gas 120 vent, comprising a cover therefor mounted on the vent head through the medium of an opening therein through which the gas pipe extends, and a cap overlying the said cover also having an opening through which the 125 gas pipe extends.

8. In a gas or the like venting device, a 130 vent head having a bore, a gas pipe communicating therewith, a gas vent in said head to one side of the gas pipe bore and commun-

icating therewith internally of the vent head, a valve seat on the vent head around the area of the gas vent, and a valve disc for the gas vent mounted on said seat through the medium of an opening therein through which the gas pipe extends.

9. In a gas or the like venting device, a vent head having a bore, a gas pipe communicating therewith, a gas vent in said head to one said of the gas pipe bore and communicating therewith internally of the vent head, a valve seat on the vent head around the area of the gas vent, a valve disc for the gas vent mounted on said seat through the medium of an opening therein through which the gas pipe extends, and a cap for the valve disc, also having an opening through which the gas pipe extends.

10. In a gas of the like venting device, a vent head, a gas pipe bore therein, a gas pipe communicating with said bore, a gas vent in said head to one side of the gas pipe and communicating with the gas pipe in said head, and a valve for said gas vent, comprising a disc cover slidably mounted on the gas pipe.

11. In a gas or the like venting device, a vent head, a gas pipe bore therein, a gas pipe communicating with said bore, a gas vent in said head to one side of the gas pipe and communicating with the gas pipe in said head, a valve for said gas vent, comprising a disc cover slidably mounted on the gas pipe, and a cap for said disc cover also slidably mounted on said gas pipe.

12. In a gas or the like venting device, a vent head, a gas pipe bore therein, a gas pipe communicating with said bore, a gas vent in said head to one side of the gas pipe and communicating with the gas pipe in said head, and a valve for said gas vent, comprising a disc cover slidably mounted on the gas pipe through the medium of an opening therein through which said pipe extends.

13. In a gas or the like venting device, a vent head, a gas pipe bore therein, a gas pipe communicating with said bore, a gas vent in said head to one side of the gas pipe and communicating with the gas pipe in said head, and a valve for said gas vent, comprising a disc cover slidably mounted on the gas pipe through the medium of an opening therein through which said pipe extends, and a cap for said disc cover also slidably mounted on said gas pipe.

14. In a gas or the like venting device, a vent head, a gas pipe bore therein, a gas pipe communicating with said bore, a gas vent in said head to one side of the gas pipe and communicating with the gas pipe in said head, a valve for said gas vent, comprising a disc cover slidably mounted on the gas pipe through the medium of an opening therein through which said pipe extends, and a cap for said disc cover also slidably mounted on said gas pipe through the medium of an open-

ing therein through which the gas pipe extends.

15. In a gas or the like venting device, an inverted frustum-shaped vent head having a central bore in the top thereof, a gas pipe having its end inserted in said bore, a gas vent in the top of the vent head to one side of said gas pipe and communicating with the gas pipe internally of the head, a valve for said gas vent, comprising a flexible disc-like cover adapted to overlie the top of the vent head and having an opening therein through which the gas pipe extends, and a cap overlying said cover.

In testimony whereof I have signed my name to this specification on this 7th day of April, A. D. 1927.
